UNITED STATES PATENT OFFICE

GIUSEPPE BEVILACQUA, OF NEW YORK, N. Y.

NONTAMPERING SAFETY ENVELOPE

Application filed May 1, 1929. Serial No. 359,688.

- This invention relates to certain new and useful improvements in safety envelope and has for its primary object to provide an envelope construction that is closed and sealed in a manner to prevent unauthorized opening thereof or tampering with the same without giving an indication of a surreptitious effort to gain access to the contents of the envelope.
- 10 A further object of the invention is to provide a safety envelope in which an envelope formed from a blank provided with side and end flaps and constructed of the usual envelope papers has a stiffening element within the folded envelope for cooperation with a locking tongue on the closure flap to prevent opening of the flap and the removal or displacement of the locking tongue without giving an indication that someone
- 15 has tampered with the envelope in attempting to open the same.

With the above and other objects in view that will become apparent as the nature of the invention is better understood, the same 25 consists in the novel form, combination and arrangement of parts hereinafter more fully described, shown in the accompanying drawings and claimed.

In the drawings:—

30 Figure 1 is a developed plan view of the blank from which the envelope is formed showing the three sections of the locking tongue;

35 Figure 1a is a perspective view of the cardboard re-inforcing insert for the locking tongue of the envelope;

Figure 1b is a plan view of the fringed cap for the outer end of the envelope tongue;

40 Figure 2 is a plan view, similar to Figure 1 with one of the side flaps in folded position and engaged with the envelope filler with which the locking tongue is associated;

Figure 3 is a plan view similar to Figure 45 2 with the bottom flap in folded position;

Figure 4 is a plan view, similar to Figure 3 with the other side flap in folded position;

Figure 5 is a plan view of the envelope, similar to Figure 4 with the upper or closure 50 flap and locking tongue in folded position;

Figure 6 is a cross-sectional view taken on line 6—6 of Figure 2;

Figure 7 is a cross-sectional view taken on line 7—7 of Figure 3;

Figure 8 is a cross-sectional view taken on line 8—8 of Figure 4;

Figure 9 is a cross-sectional view taken on line 9—9 of Figure 5;

Figure 10 is a developed plan view of the 60 cardboard insert for the envelope with which the locking tongue is associated; and

Figure 11 is a plan view of the cardboard filler in folded position ready for insertion in the envelope.

As shown more clearly in Figure 1, the envelope is formed from a blank comprising a rectangular front wall 1 carrying side flaps 2 and 3 movable upon the lines 4 and 5 respectively, a bottom flap 6 foldable upon the line 7 and a top or closure flap 8 foldable upon the line 9.

The envelope blank is formed of the usual envelope paper and has a comparatively thin cardboard filler placed therein and designed for interlocking engagement with a locking tongue on the closure flap 8, the filler shown in Figures 10 and 11 comprising the sections 10 and 11 angularly cut at opposite side edges thereof as at 12 foldable upon the line 13 to the position shown in Figure 11 forming 80 lower corner tabs 14, the upper folded edge of the section 11 of the filler terminating below the upper edge of the section 10. V-shaped notches 15 extend into the section 11 of the upper folded edge thereof as shown in Figure 11 to provide a central tab 16 for purposes presently to appear. Side notches 17 are formed in the upper section 10 of the filler defining a central connecting neck 18 for an upper cross-head or strip 19. The

filler is placed in the envelope with the section 10 adjacent the front side 1 of the envelope and with the cross-strip 19 adjacent the fold line 9 for the closure flap 8. The side flap 2 of the envelope is provided with a centrally disposed horizontal slot 20 spaced below the upper edge of the slot so that when the flap is folded onto the front side 1, the slot will be centrally disposed between the fold lines 4 and 5. Another slot 21

95

100

is formed in the flap 2 above the slot 20 with the upper inner wall thereof cut away at 22 and opening at the upper edge of the flap providing side tongues 23. With the filler in position upon the front wall 1 of the envelope, the side flap 2 is folded on the line 4 and the neck 18 of the filler is positioned in the slot 21 of the flap 2 with the tongues 23 positioned beneath the cross strip 19 as shown in Figure 2, the upper end of the tab 16 of the filler being disposed adjacent the lower edge of the slot 20 as illustrated. The flap 2 is of an area substantially equal to the front wall 1 of the envelope and is gummed at its outer edge as at 24 to be adhesively secured to the adjacent portion of the front wall 1.

The lower flap 6 is cut away at one end as at 25 for the saving of material and design purposes, while the lower edge is cut away as 26 providing a clearance for the cross strip 19 of the filler when the flap 6 is folded, the flap being provided with a slot 27 registering with the slot 20 in the flap 2 while the edges of the flap 6 are gummed as at 28, for adhesive attachment to the adjacent face of the flap 2.

The side flap 3 has its lower edge cut away as at 29 and the upper edge cut away at 30 providing a clearance for the cross strip 19 of the filler and is further provided with a slot 31 adapted to register with the slots 20 and 27 of the flaps 2 and 6 respectively. The edge of the flap 3 being gummed as at 32. When the side and bottom flaps are folded and sealed, the cross strip 19 of the filler is exposed as shown in Figure 4 and if desired, the name of the addressee may be written upon the cross strip.

A locking tongue 33 shown in completed form in Figures 2 to 4 is carried by the closure flap 8 and as shown in Figure 1 is formed of a central tongue section 34 carrying side tongue sections 35 foldable thereover and is stiffened by a relatively thin cardboard insert 36 shown in Figure 1a, the cardboard insert 36 being placed against the tongue section 34 with the side tongue section 35 folded thereover and adhesively retained in position. A cap 37 is folded medially upon the line 38 as shown in Figure 1b with opposite ends thereof serrated as at 39, the cap straddling the folded tongue sections 34 and 35 and secured thereon by the pin fastening 40. The lower edges of the side tongue sections 35 are similarly serrated as at 41 to provide a fringe edge for purposes now to appear. The free edge of the closure flap 8 is gummed as at 42 for adhesive attachment to the adjacent portions of the underlying flaps 2, 3 and 6 as shown in Figure 5. The closure flap 8 is folded on the line 9 and the reinforced stiffened tongue is inserted through the registering slots 20, 27 and 31 to be guided by the tab 16 of the filler for passage between the tab 16 and section 10 of the filler. The envelope filler is provided

with a slot 13a on the fold line 13 directly beneath the tab 16 and through which slot 13a the end of the tongue 33 is projected, the serrated or fringed ends 39 of the cap 37 passing through the slot 13a and spreading to prevent withdrawal of the tongue. The serrated or fringed ends 41 of the tongue section 35 pass through and engage the upper edges of the flap slots 20, 27 and 31 so that the tongue is doubly retained in assembled position to prevent unauthorized withdrawal thereof.

From the above detailed description of the invention, it is believed that the construction and operation thereof will at once be apparent and while there is herein shown and described the preferred embodiment of the present invention, it is nevertheless to be understood that minor changes may be made therein without departing from the spirit and scope of the invention as claimed.

I claim:

1. A safety envelope comprising an envelope body including a sealing flap, a stiffening filler in the body and a stiffened locking tongue on the sealing flap inserted in the body and engaged with the filler, the body further including side and bottom flaps and there being slots in the side and bottom flaps for insertion of the tongue into the body, said filler having a slotted opening therein, said tongue being flanged at each end and presenting fringed edges at opposite faces thereof for cooperation with the walls of the filler slot and flap slots respectively, the stiffened locking tongue comprising a central section and side sections foldable thereover and a cardboard filler for the tongue.

2. A safety envelope comprising an envelope body including a sealing flap, a stiffening filler in the body and a stiffened locking tongue on the sealing flap inserted in the body and interlockingly engaged with the filler, the body further including side and bottom flaps and there being slots in the side and bottom flaps for insertion of the tongue into the body, said filler having a slotted opening therein, said tongue being flanged at each end and presenting fringed edges at opposite faces thereof for cooperation with the walls of the filler slot and flap slots respectively, the stiffened locking tongue comprising a central section and side sections foldable thereover and a cardboard filler for the tongue.

3. A safety envelope comprising an envelope body including a sealing flap, a stiffening filler in the body and a stiffened locking tongue on the sealing flap inserted in the body and engaged with the filler, the body further including side and bottom flaps and there being slots in the side and bottom flaps for insertion of the tongue into the body, said filler having a slotted opening therein, a cap on the tongue and said cap and inner end of

- the tongue being flanged for cooperation with the walls of the filler slot and flap slots respectively, the stiffened locking tongue comprising a central section and side sections foldable thereover and a cardboard filler for the tongue, and the flanged cap comprising a strip of paper serrated at its ends and inclosing the outer end of the tongue with the serrated ends expanded outwardly.
- 5 4. A safety envelope comprising an envelope body including a sealing flap, a stiffening filler in the body and a stiffened locking tongue on the sealing flap inserted in the body and interlockingly engaged with the
10 filler, the body further including side and bottom flaps and there being slots in the side and bottom flaps for insertion of the tongue into the body, said filler having a slotted opening therein and a cap on the tongue and
15 said cap and inner end of the tongue being flanged for cooperation with the walls of the filler slot and flap slots respectively, the stiffened locking tongue comprising a central section and side sections foldable there-
20 over and a cardboard filler for the tongue, and the flanged cap comprising a strip of paper serrated at its ends and inclosing the outer end of the tongue with the serrated ends expanded outwardly.
25

30 In testimony whereof I affix my signature.
